UNITED STATES PATENT OFFICE

EDWARD W. POERNER, OF EAST ORANGE, NEW JERSEY, ASSIGNOR TO ARTCRAFT METAL STAMPING CORPORATION, A CORPORATION OF NEW YORK

DESIGN FOR A LIGHTING FIXTURE

Application filed May 31, 1930. Serial No. 35,866. Term of patent 3½ years.

To all whom it may concern:

Be it known that I, EDWARD W. POERNER, a citizen of the United States, and a resident of East Orange, in Essex County and in the State of New Jersey, have invented a new, original, and ornamental Design for Lighting Fixtures, of which the following is a specification, reference being had to the drawing forming a part thereof;

Figure 1 is a side elevational view of the lighting fixture; and

Figure 2 is a diagrammatic top plan view of the same. The dominant feature of the design consists in the employment of two glass globes A and B, one above the other, separated by an opaque band C and received within outer frame members D and E, respectively.

I claim:

The ornamental design for a lighting fixture substantially as shown and described.

EDWARD W. POERNER.
